CLAIM

The ornamental design for an oral care implement, as shown and described.

DESCRIPTION

FIG. 1 is a front perspective view of an oral care implement according to a first embodiment of our new design; FIG. 2 is a rear perspective view thereof; FIG. 3 is a front view thereof; FIG. 4 is a rear view thereof; FIG. 5 is a left side view thereof; FIG. 6 is a right side view thereof; FIG. 7 is an enlarged top view thereof; FIG. 8 is an enlarged bottom view thereof; FIG. 9 is a front perspective view of an oral care implement according to a second embodiment of our new design; FIG. 10 is a rear perspective view thereof; FIG. 11 is a front view thereof; FIG. 12 is a rear view thereof; FIG. 13 is a left side view thereof; FIG. 14 is a right side view thereof; FIG. 15 is an enlarged top view thereof; and, FIG. 16 is an enlarged bottom view thereof.

The grayscale depicted in the drawings is to show contrast in appearance.

1 Claim, 8 Drawing Sheets
